UNITED STATES PATENT OFFICE.

WALTER R. STERRETT, OF CARNEGIE, PENNSYLVANIA, ASSIGNOR TO H. L. DIXON COMPANY, OF CARNEGIE, PENNSYLVANIA, A CORPORATION OF PENNSYLVANIA.

LEER CONVEYER.

Application filed March 18, 1921. Serial No. 453,457.

To all whom it may concern:

Be it known that I, WALTER R. STERRETT, a citizen of the United States, residing at Carnegie, in the county of Allegheny and State of Pennsylvania, have invented a new and useful Improvement in Leer Conveyers, of which the following is a full, clear, and exact description, reference being had to the accompanying drawings, forming part of this specification, in which—

Figure 1 is a transverse section, partly broken away, of a leer embodying my invention;

Figure 2 is a plan view also partly broken away, showing a portion of the conveyer;

Figure 3 is a transverse section, partly broken away, of a conveyer embodying my invention, the plane of section being on the line III—III of Figure 4;

Figure 4 is a longitudinal section on the line IV—IV of Figure 3;

Figure 5 is a detail sectional view showing one of the fastenings;

Figure 6 is a plan view showing portions of two pan sections; and

Figure 7 is a diagrammatic view illustrating one manner in which the conveyer pans may adjust themselves.

My invention has relation to conveyers for leers such as glass annealing leers; and is particularly adapted for use in extra wide leers. Heretofore considerable difficulty has been experienced in the operation of wide leers. In such leers the conveyer pans tend to sag greatly at the middle portions thereof, and it has been difficult to provide a satisfactory support at such portions. The ordinary supporting castor-wheels which have been provided are objectionable in that, owing to the warping action of the heat on the tracks, as well as upon the pans, the supporting wheels cannot be kept in contact with the track, the usual result being that some of the wheels at least are in contact only part of the time. Furthermore, it is practically impossible in the operation of such conveyer to maintain the same length and load upon each of the runs of the carrying and supporting chains. This tends to distort the pans and throws unequal stresses on the chains. This distortion is also objectionable as it throws the upper surfaces of the pans out of a true plane and thereby forms upstanding edges or shoulders preventing the charging of articles into the leer.

My invention is designed to overcome these difficulties by providing a conveyer in which the pans are formed in two or more separate sections transversely, these sections being connected to the carrying and supporting chains in a manner which will permit of horizontal and vertical movements of the pans relative to the chains.

My invention also provides means whereby a proper arrangement of supporting wheels may be placed underneath the intermediate portions of the pans and be maintained in contact upon the tracks upon which they travel.

Referring to the accompanying drawings in which I have shown a preferred embodiment of my invention, the numeral 2 designates the frame of the leer which may be of any usual or desired construction, my invention being applicable to various types of leers but having nothing to do with the construction of the leer itself.

In the particular construction which I have shown, each of the leer pans is divided into two sections 3 and 4, these sections being carried upon the three runs of chain 5, 6 and 7. These runs may be of any usual construction, the links thereof carrying suitable journals for the wheels 8, which travel on the channel tracks 9.

The pan sections 3 and 4 are secured to the horizontally directed flanges 10 of the chain links, by means which will permit the pan sections to adjust themselves, both horizontally and vertically with respect to the chains. In the particular construction shown, each of these fastenings comprises a screw bolt 11 whose head is seated in a countersunk depression 12 of the pan, this counter-sunk portion 12 fitting loosely within a conical opening 13 formed in the flange 10, as clearly shown in Figures 3 and 5. These screw bolts are secured by the nuts 14.

It will be readily seen that this mode of attachment permits quite a considerable movement of the pan sections horizontally with reference to each other, as indicated by the dotted lines in Figure 6; and it also permits a relative vertical movement between the pan sections and the chains.

In practice it is impossible to keep the three chains 5, 6 and 7 of exactly the same length, the result being that with single transversely extending pans, the chains exert a varying pull upon the pans. In Figure 7

I have shown how my improved construction readily permits the pans to adapt themselves to variations in the length of the chains, thereby making it possible to maintain all 5 of the chains under the same tension. In this figure each of the broken transverse lines indicates two of the pan sections; and it will be noted that as these sections pass from the driving wheels 15 to the idler 10 wheels 16, the sections of each pair assume an increasing angularity with respect to each other, this movement compensating for the varying lengths of the different runs of chain, and enabling the maintenance of uniform load conditions as pointed out.

My invention provides a leer conveyer which can be used in leers of any desired width, each pan being formed in as many sections as may be desired. The invention 20 greatly improves the operation of the leer by insuring proper movement of the conveyer at all times, and also greatly increases the life of the conveyer.

I do not wish to limit myself to the particular construction which I have herein shown and described, as it will be manifest that various changes can be made in the construction of the runs, the form and shape of the pans, and in the manner of attaching the 30 pans to the runs, without departing from the spirit and scope of my invention as defined in the appended claims.

I claim:

1. A leer conveyer having pans which are 35 formed in separate transverse sections, and a common supporting chain to which the inner end of each pan section is connected, substantially as described.

2. A leer conveyer having pans which are 40 formed in separate transverse sections, and supporting chains to which each end of each pan section is connected, the connections between the pans and the chains having means for permitting the pan sections to move relatively to the chains, substantially as described.

3. A leer conveyer having pans which are 45 formed in separate transverse sections, and supporting chains to which each end of each pan section is connected, the connections between the pans and the chains having means for permitting the pan sections to move relatively to the chains in both a horizontal and a vertical direction, substantially as described.

4. A leer conveyer having pans which are 55 formed in separate transverse sections, and supporting chains to which each end of each pan section is connected, the connections between the pans and the chains having means for permitting the pan sections to move relatively to the chains, the ends of adjacent pan sections being connected to a chain which is common to both sections, substantially as described.

5. A leer conveyer comprising a plurality of carrying and supporting chains, pans carried by said chains and fastening devices for connecting the pans to the chains, said devices having sufficient play to permit the 70 pans to move relatively to the chains in both a vertical and a horizontal direction, substantially as described.

6. A leer conveyer comprising a plurality of carrying and supporting chains, pans carried by said chains and fastening devices for connecting the pans to the chains, said devices having sufficient play to permit the 75 pans to move relatively to the chains in both a vertical and a horizontal direction, each 80 of said pans being formed in a plurality of separate sections, substantially as described.

7. In combination, a leer, and a heat resisting conveyer therein, said conveyer having its pans formed in separate transverse 85 sections relatively movable to different angular positions, substantially as described.

8. In combination, a leer, and a conveyer therein, said conveyer having its pans formed in separate relatively movable transverse sections with adjacent ends of said sections secured to a common means, substantially as described.

9. In combination, a leer, a conveyer comprising carrying chains mounted therein, 95 and sectional pans loosely secured to said chains to permit relative horizontal and vertical movement of the pans, substantially as described.

10. In combination, a leer, a conveyer 100 therefor comprising at least three flexible runs, means for driving said runs, and a plurality of transversely divided supporting members flexibly secured to said runs to permit relative angular movement therebetween 105 whereby all of the runs may be maintained under substantially the same load, substantially as described.

11. A conveyer comprising at least three flexible runs, means for driving said runs, 110 and a plurality of transversely divided supporting members secured to said runs to permit relative vertical and horizontal movement between said members and runs whereby all of the runs may be maintained under 115 substantially the same load, substantially as described.

12. In combination, a leer, a conveyer therefor comprising at least three flexible runs, means for driving said runs, and a 120 plurality of transversely divided supporting pans flexibly secured to said runs to permit relative angular movement therebetween, whereby warping of the runs is prevented and flat article receiving surfaces are insured, substantially as described.

In testimony whereof, I have hereunto set my hand.

WALTER R. STERRETT.
